UNITED STATES PATENT OFFICE

ROY E. CUMMINGS AND JOSEPH V. SULLIVAN, OF EASTPORT, MAINE.

COMBINATION WINDOW SCREEN, WINDOW SASH, AND VENTILATOR.

Application filed May 28, 1921. Serial No. 473,538.

To all whom it may concern:

Be it known that we, ROY E. CUMMINGS and JOSEPH V. SULLIVAN, citizens of the United States, residing at Eastport, in the 5 county of Washington and State of Maine, have invented certain new and useful Improvements in Combination Window Screens, Window Sashes, and Ventilators, of which the following is a specification, 10 reference being had therein to the accompanying drawings.

This invention relates to a combination window-screen, window-sash and ventilator, and has for its object the production of a 15 simple and efficient device that can quickly be placed in a window-frame, or removed therefrom, for the purpose of ventilating a room.

Another object of the invention is the 20 provision of a detachable window-sash that can be quickly applied to a window-frame, whereby a room can be ventilated without permitting rain to enter the room, or causing drafts in the room, direct upon a person, or persons.

With these and other objects in view, our 25 invention comprises certain novel combinations, constructions and arrangements of parts as will be hereinafter described, illustrated in the accompanying drawings, and more particularly pointed out in the appended claims.

In the drawings:

Figure 1 is a view in elevation, partly 35 shown in section, of an apparatus constructed in accordance with the present invention.

Figure 2 is a sectional view, taken on line 2—2, Fig. 1, looking in the direction 40 of the arrows.

Figure 3 is a vertical, sectional view, taken on line 3—3, Fig. 1, and looking in the direction of the arrows, as the apparatus appears in open position.

Figure 4 is a fragmentary, sectional view, taken on line 4—4, Fig. 3, and looking in the direction of the arrows.

Figure 5 is an enlarged, fragmentary, sectional view of the apparatus, showing 50 the hinged window-sash in a closed position.

Referring to the drawings by numerals, 1 designates the window-screen frame, and 2 is the window-sash frame, constituting 55 a "ventilating frame"; this frame 2 is hinged, at 3, within the primary or screen-

frame 1; it will, therefore, be perceived that we have a primary frame, constituted by screen-frame 1, in which an auxiliary frame, constituted by window-sash frame 2, is 60 hingedly positioned. We use the term "window-sash frame" in a broad sense in this specification and the appended claims, for this frame 2 could be of a solid structure and yet perform its function in the 65 ventilator apparatus that we have perfected. We prefer to use a window-pane 4 in this frame so that a person can readily see through the entire apparatus; therefore, by using a pane 4, the vision of a person in a 70 room, looking through the apparatus when it is in position within the window-frame, will not be obstructed.

Screws 5 are used to fasten the upper strip 6 (constituting part of the frame) in 75 position; if the pane 4 is broken, the screw 5 can be removed, the strip 6 lifted off the frame, whereby a new pane can be easily assembled with the window-sash frame 2, forming a part thereof. 80

An adjustable extension device 7 is formed upon one end of the primary or window-screen frame 1, and this extension device includes a strip 8 fastened by a fabric cover 9, to the end of frame 1, and positioned in 85 sockets 10, in strip 8 are pins 13; in the end of frame 1, are coil springs 12, and pins 13 extend from the strip 8 within the springs 12, to guide the springs when they are depressed snugly into the sockets 10 and 90 11. This extension device 7 permits the apparatus to be quickly fitted into the window frame.

On the other end of the primary or window-screen frame 1 may be placed a 95 strip 14, which strip 14 is provided with pins 15 extending into the frame 1. It will be obvious that any number of such strips 14 may be attached to the end of the window frame for increasing its size, without departing from the spirit or scope of the present invention.

Flexible or fabric strips 16 are fastened, preferably by tacks 17, to the inner, vertical edges of the primary or screen frame 1 just 105 behind the wire screening or mesh 18. This mesh 18 is held in place by a suitable beading 19, which beading 19 is secured to the front of the screen frame 1. Additional tacks 17, Fig. 3, are used to secure the flexible or fabric strips 16 to the inner face of the window-sash frame 2. 110

2

Eye screws 20 are fastened to the inside of the primary or screen frame 1, near its upper corners and close to the wire mesh 18. Eye screws 21 are arranged in pairs and are secured to the inner face of the auxiliary or sash frame 2 at its upper corners; the eye screws 21 are placed in alignment so that the tightly wound coil spring 22 is threaded through the inner eye screw 21 of each pair 5 and permanently fastened to the outer eye screw, as clearly shown in Fig. 5; the other end of spring 22 is fastened to an eye screw 20. It will be understood that the structure 10 at both ends is the same, as two coil springs 22 are used and the peculiar positioning of the eye screw is of importance inasmuch as the upper ends of the flexible or fabric strips 16 are over the coil springs, and when the hinged frame is closed, the flexible or fabric 15 strips 16 are away from the meeting edges of the screen frame 1 and the sash frame 2, whereby no obstruction occurs during the closing action; in other words, the flexible ends, whereby the side draft is prevented, of 20 the apparatus, when in closed condition, are placed well out of the way and permit of such closing as will produce an efficient apparatus. It is to be noted that the eye screws on the primary frame 1 are at right 25 angles to the eye screws on the auxiliary frame 2, and from practical experience, we have found that this peculiar arrangement 30 produces a very efficient and durable structure.

35 To hold the hinged, auxiliary frame in an open position, short pivoted rod 23 can be swung to the position shown in Figs. 1 and 3, or long, pivotally-mounted rod 24 may be used if a greater opening is desired.

40 We claim that our apparatus distinguishes from the ordinary screen in many respects, among which can be pointed out the fact that with an ordinary screen the air rushing through the same instead of going 45 upwardly so as not to blow directly against a person that may be in the room; with our apparatus, when in an open condition, air rushing through the wire mesh will strike the auxiliary or "ventilator frame" 2 and 50 said air is shot upward, almost perpendicularly into the room. The collapsible ends, constituted by the flexible or fabric strips 16, prevent the air in motion from escaping sideways, so that all fresh air, coming into 55 the room through the wire mesh or screening must, of necessity, be shot upward. It is also obvious that in case of sudden storms, no rain (water) can get into the room to 60 destroy carpets, or furniture, or other decorations, because that which does come through the screen strikes upon the glass or pane 4 and falls outward, or outside of the building. In the event of very severe 65 storms or when the ventilation of the room is such that no further air is desirable, the

hinged, auxiliary frame 2 may be closed and secured in place by the pivotally mounted button 25 on the primary screen frame 1 without removing the apparatus from the window, thus stopping all ventilation 70 through our apparatus.

Our apparatus is designed to be of very great value and service in hospitals or rooms where persons are sick in bed in that they are protected from drafts. In offices where 75 persons occupy desks near windows they are protected from drafts and papers will not be blown from their desks and scattered about the room.

The apparatus is also of inestimable value 80 when it is used to ventilate a room and the occupants of the room are asleep, or when a sudden rain storm arises because of the absolute protection afforded by this invention, 85 as hereinbefore explained.

While we have described the preferred embodiment of our invention, and have illustrated the same in the accompanying drawings, certain minor changes or alterations may appear to one skilled in the art to 90 which this invention relates, during the extensive manufacture of the same and we, therefore, reserve the right to make such alterations or changes as shall fairly fall 95 within the scope of the appended claims.

What we claim is:

1. In an apparatus of the class described, the combination of a primary frame, an auxiliary frame movably mounted upon said primary frame, eye screws fastened to the primary frame, pairs of eye screws fastened to the auxiliary frame, coil springs fastened at their inner ends to the eye screws on the primary frame, each of said coil springs threaded through one of the eye screws of a pair and fastened permanently to the eye screws of the same pair, and fabric strips fastened to the coil spring and also fastened to the primary and auxiliary frames. 100

2. In an apparatus of the class described, 105 the combination of a primary frame provided with a wire mesh over its front, an auxiliary frame hingedly mounted within the primary frame, eye screws fastened in the primary frame contiguous to the wire 110 mesh, a plurality of pairs of eye screws fastened to the inner face of the auxiliary frame near its upper corners, said pairs of eye screws positioned at right angles to the eye screws on the primary frame, said 115 coil springs threaded through the inner eye screws of the pairs and fastened permanently to the outer screws of the pairs, fabric strips fastened over the coil springs between the inner eye screws of the 120 pairs and the eye screws on the primary frame, and means fastening the strips throughout their heights to the primary and auxiliary frames, substantially as shown and 125 described.

3. In an apparatus of the class described, the combination of a primary frame, an auxiliary frame hingedly mounted upon said primary frame, flexible strips fastened to the 5 end portions of the auxiliary frame and to the primary frame, and means operating to fold the strips in a single fold inwardly from the ends of the auxiliary frame when the auxiliary frame is moved to a closed position 10 on the primary frame, as and for the purposes set forth.

4. In an apparatus of the class described, the combination of a primary frame, an auxiliary frame hingedly mounted upon said 15 primary frame, coil springs having their

ends connected to said frames adjacent the upper corners thereof, flexible strips secured to the end portions of the auxiliary frame and to the primary frame and to said springs, and means engaging said 20 springs intermediate their ends and pulling upon the springs so that when the auxiliary frame is moved to a closed position upon the primary frame the flexible strips will be folded inwardly from the ends of the auxiliary frame, as and for the purposes set forth. 25

In testimony whereof we hereunto affix our signatures.

ROY E. CUMMINGS.

JOSEPH V. SULLIVAN.
